UNITED STATES PATENT OFFICE

JAMES H. HAVER, OF NEWPORT, KENTUCKY

APPARATUS FOR HARDENING STEEL

Application filed January 15, 1930. Serial No. 420,924.

This invention relates to apparatus for hardening steel and an object of the invention is to provide an apparatus that is very simple in operation, strong, compact and durable, thoroughly reliable for its intended purpose, very efficient in operation and comparatively inexpensive to manufacture.

Another object of the invention is to provide for hardening steel by subjecting steel to a liquid or vapor bath under pressure to eliminate checking, cracking and to insure uniform quenching of all parts of the steel being treated regardless of the contour, shape and thicknesses thereof.

With the foregoing and other objects in view, the invention consists of a novel construction, combination, arrangement of parts, as will be hereinafter more specifically described and illustrated in the accompanying drawings, wherein is disclosed an embodiment of the invention, but it is to be understood that changes, variations, and modifications may be resorted to without departing from the spirit of the claims hereunto appended.

In the drawings:

Figure 1 is a side elevation, partly broken away, of the apparatus in accordance with the present invention,

Figure 2 is an enlarged vertical section in detail of the front portion of the apparatus,

Figure 3 is an enlarged vertical section in detail, partly broken away, of the rear end of the cylinder,

Figure 4 is a vertical section taken substantially on line 4-4 of Figure 2,

Figure 5 is a vertical section taken substantially on line 5-5 of Figure 3,

Figure 6 is a front elevation of the apparatus having parts broken away,

Figure 7 is a rear end elevation of the cylinder.

It is well known in the heat treating art that submerging hot castings in liquid baths at atmospheric pressure cause bubbles of gas or vapor to adhere to the surface of the casting which cause uneven quenching of the casting. It will therefore be obvious that the primary feature of the present invention is to provide for liquid or vapor quenching

under pressure to eliminate the uneven quenching caused by open liquid baths.

Referring to the drawings in detail, 10 indicates an elongated flat pedestal supported on four legs 11. A supporting base 12 is bolted to the pedestal 10 by a plurality of bolts 13 and the upper end of the base 12 merges in a hollow tubular support 14 which is interiorly threaded as at 15, 16 at its opposite ends.

Adjacent the inner end of the threaded portions 15, 16 there are formed a pair of annular, outstanding shoulders 17, 18 and between the shoulders and the inner ends of the threaded portion there are provided pockets 19, 20.

Extending axially through the tubular support 14 is an elongated, hollow cylinder indicated generally at 21, the periphery of which is slidably supported on the peripheral edges of the shoulders 17, 18.

A gland nut 22 threadably engages in the threaded end 15 of the support 14 and the inner end thereof presses a packing gland 23 against the shoulders 17 to provide a slide- 75
able support for the cylinder 21. To the opposite threaded end 16 of the support 14, one end of a packing sleeve 24 is connected and this inner end presses a fiber gland 25 against the shoulder 18 to form a tight joint and 80 bearing for the cylinder 21.

The outer free end of the sleeve 24 is threaded as at 26 and threadably mounted thereon is a gland nut 27 holding a gland packing 28 against the inner end of the outer 85 free end of the sleeve 24. The sleeve 24 forms an additional bearing surface for the cylinder which cylinder 21 extends therethrough.

The peripheries of the gland nuts 22, 24 and 27 are provided with openings 29, so that 90 the nuts and sleeve may be tightened for making a tighter joint to compensate for contraction and expansion in the apparatus.

The front end of the elongated cylinder 21 is peripherally threaded at 30 and threadably connected thereto is a cylinder head 31. Extending axially through the cylinder head 31 are a pair of circular openings 32, 33 enlarged and peripherally threaded on their outer ends as at 34, 35. Gland nuts 36 thread- 100

ably engage with the enlarged portions 34, 35 and press gland packings 37 in the openings 32, 33 to provide a tight joint.

A pair of tubular rods 38, 39 extend 5 through the gland nut 36 and the openings 32, 33 interiorly of the cylinder 21 and are connected in a manner to be presently described, with stationary piston heads indicated generally at 40 on which the cylinder 10 21 slides. The piston rods 38, 39 are suitably supported on a standard 41, the lower end of which is secured to the pedestal 10.

Piston rods 38, 39 project through the standard 41 and on the outer free ends thereof there is connected a pair of three-way valves 42, 43. To these valves 42, 43 are connected levers 44, which in turn are connected with rods 45 that are slidably supported in openings 46 extending through the 20 flange 47 of the cylinder head 31. The rod 45 is connected with the valve 42 and has a nut 48 on its inner end that abuts the flange 47 while the rod 45 that connects with the valve 43 has a nut 49 forwardly of the flange 47 25 and intermediate its ends to abut the flange 47.

The inlet passage of each of the three-way valves 42, 43 are connected with air supply conductor pipes 50, 51, while another passage 30 of the valve is connected to exhaust conductor pipes 52, 53 and the third valve passage of each of the valves 42, 43 are connected with the outer end of the tubular piston rods 38, 39.

35 The inner end of the hollow piston rod 39 is open and communicates with an expansible chamber 54 formed between the head 55 welded as at 56 across the interior of the elongated cylinder 21 intermediate 40 its end.

The inner end of the compartment is bridged by the stationary piston head 40 on which the cylinder 21 is slidable. The piston head 40 is formed of a central disk 45 57 formed with a piston ring 58 about its peripheral edge. To insure a tight fit of the piston head within the cylinder there are a pair of leather disks 59, 60 held in slidably abutment with the cylinder walls 50 by a pair of plates 61, 62 and are secured to the central disk 57 by a plurality of screws 63. The central disk 57 is provided with a pair of peripherally threaded openings, spaced diametrically from each other in 55 which the inner end of the hollow piston rods 38, 39 are rigidly secured.

The inner end of the hollow piston rod 38 is closed by a screw cap 64 while the inner end of the piston rod 39 is open and communicates with the chamber 54. Adjacent the point where the inner end of the piston rod 38 extends through a piston head 40 there is an opening 65 that is in communication with chamber 66 formed between the 60 piston head 40 and the cylinder head 31.

This chamber 66 is expansible like the chamber 64.

From the foregoing it will be seen that the stationary piston 40 forms a partition wall that divides the expansible chambers 70 54 and 66 and by the coordination of the valves 42, 43 with the inlet air supply pipe 50, 51, the cylinder is caused to move inwardly and outwardly on the piston head 40 and the support 14.

While the invention has been described as using an air pressure for operating the cylinder 21, it is within the contemplation thereof to use any fluid whether it be gas or liquid.

Intermediate the end of the elongated cylinder 21, there is formed a heat treating chamber 67 by radial partition walls 68, 69 welded as at 70 to the inner periphery 75 of the cylinder wall.

On the upper face of the chamber 67 there is provided a removable cap 71 through which the dies or other castings are charged into the chamber 67. On the diametric opposite side walls of the chamber 67 are formed a pair of openings 72, 73 through which is admitted to the chamber, the quenching liquid or vapor to be presently described.

At the inner end of the stroke of the cylinder 21, these openings 72 register with openings 74 extending through the diametrically opposite sides of the support 14 and connected to these openings 74 are branch pipes 75, 76 that merge with conductor pipe 77 leading from the pressure tank 78 disposed above the support 14.

The rear end of the cylinder 21 is closed by an integral back wall 79 through which extends a pressure gauge pipe 80, the inner end of which is threadably supported in an opening 81 in the partition wall 69 and the conductor pipe 80 communicates with the chamber 67. On the outer end of the conductor 80 is a pressure gauge 82 by which pressure in the chamber 67 is determined.

Another conductor pipe 83 extends through the rear wall 79 and the inner end thereof is threadably supported in an opening 84 that extends through the partition wall 69 adjacent the lower point of the chamber 67. Through this conductor pipe 83 is set up a circulation of vapor or liquid through the apparatus depending upon whether the steel in chamber 67 is being quenched in liquid or vapor. At the outer end of conductor pipe 83 there is a valve 84 connected to control the circulation of the fluid and connected to this valve is one end of an armored flexible conductor pipe 85, the upper end of which leads into the liquid storage tank 86 supported above the pressure tank 78.

There is a valve controlled conductor pipe 87 that connects tank 86 with the pressure 130

tank 78. A suitable charging cap (not shown) is detachably mounted on tank 86 to replenish the supply of the quenching liquid.

5 The tank 86 may be of any suitable shape and contains any quenching fluid desired such as water or oil. To one end of the pressure tank 78 is connected a conducting pipe 89 which is valve controlled and this pipe 89 10 leads from a suitable air supply. Air pressure is maintained on tank 78 of about one hundred and seventy five pounds.

In event steel is to be quenched in a liquid bath then the valve in the conductor pipe 87 15 is opened to a point where the pressure tank 78 will be substantially full of liquid. If a vapor quenching bath is desired then a small stream of quenching liquid is permitted to flow into pressure tank 78 whereupon it will 20 be vaporized.

It therefore follows that the quenching medium whether it be in liquid or vapor phase is maintained in the apparatus at approximately one hundred and seventy five pounds 25 pressure. The length of the stroke of the cylinder 21 should be such that the openings 72, 73 in chamber 67 should register with openings 74 in the support 14 at the inner end of the stroke and therefore the displacement in the expansible chamber 64 and 66 30 should accommodate this registration.

The partition wall 55 and the cylinder head 31 being spaced from the stationary piston head 40 is provided to accomplish this 35 movement.

The left hand end of the stroke and the parts in assembled relation with respect to each other is shown in Figure 1 of the drawings. In operating the machine in accordance with the present invention, the steel dies or other castings or castings or forgings to be treated are first heated to a point within their critical temperature ranging from fourteen hundred degrees Fahrenheit to twenty one 40 hundred and fifty degrees Fahrenheit depending upon the chemical analysis of the steel, sufficiently long to allow the rearrangement of the crystalline structure thereof, is placed in the chamber 67.

50 Air is connected to conductor pipes 50, 51. The three way valve 43 is then opened to the position shown in Figure 1 by hand, whereupon air will be conveyed to expansible chamber 54 and the cylinder 21 will be moved to the left. At the same time valve 43 is opened, 55 the three way valve 42 is in exhaust position from the previous stroke, and relieves the pressure in chamber 66 as cylinder 21 moves to the left. At the end of the left hand stroke, 60 the parts are so constructed as to bring openings 73 into registration with quenching fluid openings 74 in the support whereupon chamber 67 receives the inflowing quenching liquid or vapor under the aforementioned pressure.

65 The quenching liquid or vapor sets up a

circulation through outlet conductor 83, flexible conductor 85 and back into the liquid receiving tank 86 whereby the steel in the compartment 67 is subjected to a circulating quenching fluid, which may be either liquid 70 or vapor, under pressure.

The rapidity of circulation is controlled by valve 84 on the end of conductor pipe 83. At the end of the left hand stroke flange 47 abuts the nut or lug 49 and automatically 75 moves the valve 43 to exhaust position to relieve the pressure in chamber 54 on the right hand stroke.

When the steel in chamber 67 has been quenched for the desired time, valve 42 is 80 then operated by hand to open position which would be to the left as shown in Figure 1 of the drawings, whereupon air flows into chamber 66 moving cylinder 21 to the right.

At the end of the right hand stroke flange 85 31 abuts lug 48 moving three-way valve 42 to the exhaust position ready to begin another cycle of operation when valve 43 is turned by hand to open position, after the die or other casting or forging and then removed 90 from the quenching chamber 67.

It is to be understood that by describing in detail herein, any particular form, structure, arrangement it is not intended to limit the invention beyond the terms of the several 95 claims of the requirement of the prior art.

Having thus described my invention, what I claim as new is:

1. A steel hardening apparatus comprising 100 a support, a hollow cylinder mounted for reciprocation on the support, a stationary piston head mounted interiorly of the cylinder and on which the cylinder is movable, a partition wall disposed in the cylinder intermediate its ends forming expansible chambers on the opposite sides of the piston head, hollow piston rods secured to the piston head one communicating with each expansible chamber and providing means for alternately supplying and exhausting fluid from the expansible chambers, a quenching vapor pressure tank in communication with opening in the support, and an independent heat treating chamber in the cylinder having means thereon that communicates with the vapor pressure tank through said openings in the support when the cylinder is at the inner end of its stroke for receiving quenching vapor under pressure.

110 115 120 125 130
2. A steel hardening apparatus comprising a support, a hollow cylinder mounted for reciprocation on the support, a stationary piston head mounted interiorly of the cylinder and on which the cylinder is movable, a partition wall disposed in the cylinder intermediate its ends forming expansible chambers on the opposite sides of the piston head, hollow piston rods secured to the piston head one communicating with each expansible chamber and providing means for alternately

supplying and exhausting fluid from the expandible chambers, a quenching vapor pressure tank in communication with opening in the support, and an independent heat treating chamber in the cylinder having means thereon that communicates with the vapor pressure tank through said openings in the support when the cylinder is at the inner end of its stroke for receiving quenching vapor under pressure, said first mentioned means on the free ends of the hollow piston rods.

3. A steel hardening apparatus comprising a reciprocating hollow cylinder, a stationary piston head in the cylinder dividing the cylinder into a pair of expandible chambers, a pair of hollow piston rods supported on their inner ends on the piston head, one communicating with one chamber and the other piston rod communicating with the other chamber, means for alternately supplying and discharging fluid pressure to each chamber, a heat treating compartment in the cylinder, a quenching vapor tank, and means for connecting the vapor pressure tank with the heat treating compartment at the one end of the stroke of the cylinder.

In testimony whereof I affix my signature.
JAMES H. HAFFER.
